UNITED STATES PATENT OFFICE.

LOUIS ETTLINGER, OF NEW YORK, N. Y., ASSIGNOR TO AMERICAN LITHOGRAPHIC COMPANY, OF NEW YORK, N. Y., A CORPORATION OF NEW YORK.

DESIGN FOR A CIGAR-BAND.

40,576.

Specification for Design.

Patented Mar. 15, 1910.

Application filed August 15, 1908. Serial No. 448,754. Term of patent 7 years.

To all whom it may concern:

Be it known that I, LOUIS ETTLINGER, a citizen of the United States, residing at 40 East Seventy-third street, borough of Manhattan, in the city of New York, county of New York, and State of New York, have invented a new, original, and ornamental Design for Cigar-Bands, of which the following is a specification, reference being had to the accompanying drawing, forming a part thereof.

The figure is a plan view of a cigar band showing my new design.

I claim—

The ornamental design for a cigar band as shown.

LOUIS ETTLINGER.
